DIAGNOSTIC COMPOSITION AND METHOD

Jonas Kamlet, Brooklyn, N. Y., assignor to Miles Laboratories, Inc., Elkhart, Ind., a corporation of Indiana

No Drawing. Application October 2, 1940,
Serial No. 359,345

6 Claims. (Cl. 23—230)

The present invention relates to diagnostic compositions and, more particularly, to diagnostic compositions suitable for use in the qualitative detection and quantitative estimation of acetone and acetoacetic acid in body fluids (e. g. urine, blood, cerebrospinal fluid). It has for its object to provide a simple, rapid and convenient method for performing these tests with a high degree of accuracy and specificity, and one that can readily be used by the average physician without laboratory equipment or specialized analytical training.

The detection and estimation of acetone and acetoacetic acid are of the greatest importance in diagnosing a number of pathological conditions, such as diabetes, mellitus, malnutrition, cachexia, various gastrointestinal disorders, high fevers of long duration, etc. However, the methods heretofore employed require not only some technical ability and experience, but also make use of equipment and chemicals which are not always available to the average medical practitioner. Thus, the qualitative methods described by Lange, Le Noble, Rothera, Rantzman and Kamlet based on the reaction of sodium nitroprusside with ammonia or monoethanolamine all require the use of freshly prepared reagents and a good analytical technic. The various quantitative methods (Van Slyke and Fitz, Marriott, Behre and Benedict) all require skill and equipment rarely found outside of a hospital laboratory. Fortune, United States Patent No. 2,186,902, has described a urine acetone test based on the reaction of diluted urine with a soluble nitroprusside, an ammonium salt, a soluble carbonate and a material (such as talc) that will cause the observed color to be that due to reflected light. This method is not, however, suitable for the detection of acetone and acetoacetic acid in deproteinized blood filtrate or in cerebrospinal fluid, where it can be of value in the diagnosis of meningitis.

The present invention has for its further object to provide a means whereby an unskilled person may perform a quantitative or qualitative estimation of acetone and acetoacetic acid in urine, cerebrospinal fluid or deproteinized blood filtrate, without the use of any equipment except a test-tube. It will enable the average physician to follow the course of his patient's disease and to judge the effectiveness of his treatment. The appearance of a ketosis, the phenomenon of excessive acetone and acetoacetic acid production by the body, is always a danger signal that warns of an abnormal state of metabolism that is apt to seri-

ously endanger the health of the patient if not properly and promptly diagnosed and properly treated. A simple acetone test that can be performed by the patient proper is therefore of the greatest value in preventing such conditions. This is especially true in those diabetics that require insulin injections two or three times during the day.

The most accurate method heretofore available for the qualitative detection and quantitative estimation of acetone and acetoacetic acid is that of Behre and Benedict (Journ. Lab. Clin. Med., 13, 770, 1928; Journ. Biol. Chem., 70, 487, 1926). This method is based on the reaction of acetone with salicylaldehyde in alkaline solution to give the deeply colored, orange to red compound, salicylacetone. Any acetoacetic acid in the solution is converted quantitatively to acetone by the alkali.

This method has never, however, been suitable for use by the average physician or unskilled patient. Salicylaldehyde is an unstable liquid that is highly irritating to the mucous membranes (Wohler & Frerichs, Annalen der Chemie, vol. 65, page 336), while the concentrated sodium hydroxide solutions required rapidly become attenuated by the absorption of carbon dioxide from the air. In the quantitative method, distillation apparatus and a colorimeter are required, as well.

The basis of the present invention is the finding that compositions of high sensitivity and good specificity for acetone can be obtained by mixing a member of the group consisting of the alkali metal- and alkali-earth-metal-bisulfite addition products of salicylaldehyde and a member of the group consisting of the oxides and the hydroxides of the alkali-metals and the alkali-earth metals, both in the dry state. On reaction with an aqueous fluid, such as urine, cerebrospinal fluid or blood, the bisulfite addition product of salicylaldehyde will react with the alkali, liberating free salicylaldehyde. In the presence of free alkali, the latter will then interact with any acetone present in the fluid to give the characteristic coloration.

The alkali metal- and alkali-earth metal bisulfite addition products of salicylaldehyde are obtained by dissolving equimolecular proportions of the bisulfite and salicylaldehyde in hot water, and allowing to crystallize. The addition products form stable, white compounds, very soluble in water, but slightly soluble or insoluble in all organic solvents. When reacted with water in the

presence of alkali, they form salicylaldehyde and a sulfite. The latter prevents the premature oxidation of the salicylaldehyde by atmospheric oxygen or by an oxidizing agent present in the fluid. This is often the case when potassium dichromate is added to remove traces of formaldehyde used as a preservative.

To determine qualitatively whether acetone (or acetoacetic acid) is present in a fluid, a measured amount of a composition described above, say a five grain tablet, is mixed with a measured amount of urine. In the presence of acetone (or acetoacetic acid), the color of the urine will change to orange or red. In the absence of acetone bodies, the urine will retain the characteristic yellow color of the sodium salt of salicylaldehyde.

To determine quantitatively the amount of acetone in the fluid, the orange or red color observed (which is strictly proportional in intensity to the amount of total acetone and acetoacetic acid originally present) is compared with a color chart of known concentrations of acetone in urine. This method of comparison is a direct corollary of Beer's law, on which the entire art of colorimetry is based; namely—that the amount of light absorbed in passing through a colored medium is directly proportional to the concentration of colored substance. The results of this quantitative colorimetric test may be stated in terms of milligrams per 100 cc. or as a percentage or ratio as desired.

It is obvious, of course, that diluents, excipients, dispersing agents and auxiliary substances may be incorporated into these compositions without changing the basis of the present invention. Diluents such as talc and kaolin or an alkaline metal silicate may be added to obtain a better tablet or a more stable product. Excipients such as lactose, starch and flour may be added to facilitate the formation of granules. Dispersing agents such as saponin, gelatin, agar, soap, tragacanth and gum arabic may be added to accelerate the disintegration of the tablet when placed into the fluid. Auxiliary substances, such as coloring agents or perfumes may likewise be added. These compositions may be used in the form of powder, or granules, or dispensed in capsules, or they can be pressed into tablets of such a size as is convenient for the performance of a single test.

The following example of a typical composition covered by this invention is intended to define and illustrate, but in no way to limit this invention to the reagents, proportions or conditions described therein. Obvious modifications will occur to any person skilled in the art.

Example

To a solution of 1050 grams of sodium bisulfite in 5 liters of boiling water is added 1250 grams of technical salicylaldehyde. The mixture is stirred vigorously for one hour and then steam-distilled until a test-portion of the distillate fails to show the presence of a phenol. The hot solution is then evaporated in vacuo to a volume of two liters and allowed to cool. The copious precipitate of salicylaldehyde sodium bisulfite that forms on standing overnight, is filtered off, washed with alcohol and ether and dried.

One kilogram of the dried salicylaldehyde sodium bisulfite is comminuted to a fineness corresponding to 60 mesh, and mixed with nineteen kilograms of 60 mesh powdered technical caustic soda and twenty-five hundred grams of talc.

When the mixture has become homogeneous, it is pressed into five-grain tablets.

To facilitate the disintegration of these tablets, a mechanical dispersing agent may be incorporated. This dispersing action may also be accomplished by incorporating into the composition a dry compound which, when added to water, will react vigorously with the caustic soda and effect the mechanical disintegration of the tablet.

10 Examples of such compounds are citric acid, tartaric acid, oxalic acid, potassium bisulfate, monobasic calcium phosphate, etc. In each case, it is necessary to have a large excess of caustic soda over that amount required for the stoichiometric neutralization of the acidic substance.

15 The sensitivity of this composition is such that it will detect 0.050% of acetone in urine, or 0.035% of acetone in aqueous solution.

Having described my invention, what I claim and desire to protect by Letters Patent is:

1. Diagnostic compositions comprising a dry mixture containing essentially a member of the group consisting of the alkali metal- and alkali-earth metal-bisulfite addition products of salicylaldehyde and a member of the group consisting of the alkali metal- and alkali-earth metal oxides and hydroxides, the proportions of the two materials being such that the second member is present in excess of the amount necessary to react with the first member in water to liberate salicylaldehyde and form a normal sulfite salt, and in excess to provide an alkaline solution containing said liberated salicylaldehyde upon addition of the composition to a liquid to be tested for a content of acetone and acetoacetic acid.

2. Diagnostic compositions comprising a dry mixture containing essentially the sodium bisulfite addition product of salicylaldehyde and a member of the group consisting of the alkali metal- and alkali-earth metal oxides and hydroxides, the proportions of the two materials being such that the second member is present in excess of the amount necessary to react with the first member in water to liberate salicylaldehyde and form a normal sulfite salt, and in excess to provide an alkaline solution containing said liberated salicylaldehyde upon addition of the composition to a liquid to be tested for a content of acetone and acetoacetic acid.

3. Diagnostic compositions comprising a dry mixture containing essentially the sodium bisulfite addition product of salicylaldehyde and sodium hydroxide, the sodium hydroxide being present in quantity which is in excess of the amount necessary to react with the said addition product in water to liberate salicylaldehyde and form normal sodium sulfite, and in excess to provide an alkaline solution containing said liberated salicylaldehyde upon addition of the composition to a liquid to be tested for a content of acetone and acetoacetic acid.

4. A process for testing for acetone and acetoacetic acid present in fluids which consists in adding to a measured amount of said fluid a measured amount of a composition as described in claim 1, whereby the resultant color of the fluid indicates the quantity of acetone and acetoacetic acid.

5. A process for testing for acetone and acetoacetic acid present in fluids which consists in adding to a measured amount of said fluid a measured amount of a composition as described in claim 1, to produce a color which by comparison with a color standard indicates the quan-

tity of total acetone and acetoacetic acid in the fluid.

6. A process for testing for acetone and acetoacetic acid present in body fluids which consists in adding to a predetermined amount of the body fluid a predetermined amount of a fixed proportion dry mixture containing a member of the group consisting of the alkali metal- and alkali-earth metal-bisulfite addition products of salicylaldehyde and an alkali selected from the group consisting of the alkali metal- and alkali-earth metal oxides and hydroxides, wherein the amount

of said alkali is in excess of the amount required to react with said addition product in water to liberate salicylaldehyde and form a normal sulfite salt, and in excess to provide an alkaline solution of said liberated salicylaldehyde upon addition of said mixture to an aqueous fluid to be tested for acetone and acetoacetic acid, whereby to produce a color comparable with predetermined standard colors to indicate the percentage of acetone and acetoacetic acid in the body fluid.

JONAS KAMLET.
